United States Patent Office.

CONYERS BUTTON, OF PHILADELPHIA, PENNSYLVANIA.

Design No. 3,406, dated March 23, 1869.

DESIGN FOR A STOCKING-FABRIC.

The Schedule referred to in these Letters Patent and making part of the same.

To all whom it may concern:

Be it known that I, CONYERS BUTTON, of Philadelphia, county of Philadelphia, State of Pennsylvania, have originated a new Design for a Stocking-Fabric; and I do hereby declare that the accompanying drawing, and following explanation thereof, form a full, clear, and exact description of the said design.

In the drawing, the figure represents sufficient of a stocking-fabric to illustrate my design, the main feature of which consists of a stripe, composed of the central pattern A, edged on each side by and adapted to a row of hexagonal spots B.

Irrespective of the colors employed in carrying out my design,

I claim the design for a stocking-fabric, substantially as described, and as represented in and by the accompanying drawing.

In testimony whereof, I have signed my name to this specification, in the presence of two subscribing witnesses.

CONYERS BUTTON.
